UNITED STATES PATENT OFFICE.

WILLIAM E. WINE, OF TOLEDO, OHIO.

UNCOUPLING DEVICE.

1,215,458.

Specification of Letters Patent. Patented Feb. 13, 1917.

Application filed April 3, 1916. Serial No. 88,624.

To all whom it may concern:

Be it known that I, WILLIAM E. WINE, a citizen of the United States, residing at Toledo, in the county of Lucas and State of Ohio, have invented new and useful Improvements in Uncoupling Devices, of which the following is a specification.

My invention relates to uncoupling devices for car couplers. It is the object of my invention to provide a form of coupler release which is simple, durable, cheap and efficient.

With these and other objects hereinafter explained in view my invention consists in the construction and combination of elements hereinafter described and claimed.

In the accompanying drawings which illustrate the preferred embodiment of my invention; Figure 1 is a plan view of the device applied to the end sill of a car. Fig. 2 is an elevation of same. Fig. 3 is a plan view of a portion of the device to a larger scale. Fig. 4 is an elevation of the parts shown in Fig. 3 and section on line A—A. Fig. 5 is a partial end view of the uncoupling lever bearing and partial section on line B—B of same.

Similar characters designate similar parts throughout the several figures of the drawing.

Referring now to parts by number. The hand lever 1 is pivoted by bearing 2 on the bracket 3. The inner end 4 of hand lever 1 is bent outwardly at right angles to the main portion thereof and is provided with a slot or notch 5 in which rests the coupling lever 6.

The off-set end 7 of coupler lever 6 is pivoted in hole 8 of uncoupling lever 1. The bearing 2 consists of two parts identically the same which are provided with lugs or extensions 9 adapted to engage ribs 10 on bracket 3 to limit the pivotal movement of hand lever 1. The hand lever 1 is held in position in bearing 2 by rivet or other attaching means 11. Bearing 2 being held in position on bracket 3 by bolt 12 and washer 13.

It can readily be seen that bracket 3 and bearing 2 can be made castings of any suitable material, while the hand lever 1 and uncoupling lever 6 can be made of wrought iron or steel and bent into their respective shapes with but little work.

Uncoupling levers of this same general type which are in present use are so con-

structed that it is necessary to make them of forgings entailing considerable equipment and labor for their manufacture.

In this device it can readily be understood how the parts can be manufactured at a minimum cost and at the same time make a thoroughly efficient and operable device.

Having thus described my invention, I aim in the appended claims to cover all modifications which do not involve a departure from its spirit and scope.

What I claim as new and desire to secure by Letters Patent of the United States is:—

1. In a release rigging, the combination of an uncoupling lever and means for pivotally mounting same, comprising a bearing thereon and a bracket for the reception of said bearing, said bearing being provided with means adapted to limit its pivotal movement.

2. In a release rigging, the combination of an uncoupling lever and means for pivotally mounting same, comprising a bearing thereon and a bracket for the reception of said bearing, said bearing being provided with ribs adapted to engage said bracket to limit its pivotal movement.

3. In a release rigging, the combination of a hand lever, means for pivotally mounting said hand lever comprising a bracket having a trunnion thereon, a bearing attached to said hand lever and engaging said trunnion and means for holding said bearing in engagement with said trunnion, and an uncoupling lever coöperating with said hand lever.

4. In a release rigging, the combination of a hand lever, means for pivotally mounting said hand lever, comprising a bearing thereof and a bracket for the reception of said bearing, and an uncoupling lever coöperating with said hand lever, said bearing being provided with means adapted to limit its pivotal movement.

5. In a release rigging, the combination of a hand lever, means for pivotally mounting said hand lever comprising a bracket having laterally disposed lugs thereon and a bearing attached to said hand lever provided with lugs adapted to engage said lugs on said bracket to limit its pivotal movement and an uncoupling lever coöperating with said hand lever.

6. In a release rigging, the combination with a hand lever of means for pivotally mounting said hand lever comprising a

2
bracket provided with a trunnion and laterally disposed lugs, and a bearing provided with an opening for the reception of said hand lever, said bearing comprising two 5 identical oppositely disposed portions provided with lugs adapted to engage said lugs on said bracket for limiting the pivotal movement thereof, and means for holding

said hand lever in fixed relation with said bearing.

This specification signed and witnessed this 1st day of April, 1916.

W. E. WINE.
